ADVERTISING DISPLAY-CARD
Salvatore Rizzo, 4028 W. Barry, Chicago, Ill.
Filed Mar. 27, 1961, Ser. No. 98,509
1 Claim. (Cl. 211—57)

This invention relates to an advertising display for presenting literature removable by the interested patrons of public transport facilities.

On occasion advertisers desire to make available to the patrons of public conveyances free literature explanatory of a service or product presented in the display-card. In the past this frequently has been done by stapling a stack of cards or leaflets to a display-card or placing the cards or leaflets in a pocket attached to the display-card, so that the cards or leaflets would be easily accessible to patrons possibly interested in the subject matter of the display-card.

All too often a careless attempt to obtain a card or leaflet has resulted in the dislodgment, and sometimes waste, of much, if not all, of the displayed literature.

The main objects of this invention are to provide an improved advertising display for mounting literature readily accessible for removal by interested patrons of public transport conveyances; to provide an improved advertising display-card mounting of this kind especially adapted for suspending cards suitable for subsequent mailing; to provide an improved and simple form of hook element readily attachable to a display-card, of the type conventionally used in public transport vehicles, for the suspension of "take one" literature; and to provide an improved display-card mounting of this kind which is very economical to manufacture, easy to attach to a display-card and which suspends a stack of cards for facile removal one at a time without the likelihood of dislodging the remaining cards, or dislodgment of the hook element, or mutilating the display-card itself.

In the adaptation shown in the accompanying drawings:

FIGURE 1 is a diagrammatic outline of a conventional advertising display-card and two literature-suspension mountings and attached in accordance with this invention;

FIG. 2 is an enlarged, fragmentary, vertical cross-sectional view of the same taken on the plane of the line 2—2 of FIG. 1;

FIG. 3 is a perspective view of the improved form of hooked mounting adapted for use with a display-card.

The essential concept of this invention involves a mounting element in the form of a flat plate having a portion extending outwardly from one face of the plate and in the form of an upwardly-facing forwardly-disposed hook insertable through an apertured display-card to position the plate against the back of the display-card and dispose the hook outwardly from the face of the display-card for the suspension of literature readily removable, one piece at a time, by interested persons, and also providing a mounting element which cannot be dislodged from the display-card without removal of the whole card from its seating position.

A literature-suspending display embodying the foregoing concept comprises a supporting display-card 4, a suspension element 5 and a stack of literature 6.

The display-card 4 is a piece of calendered cardboard such as conventionally used for display advertising in public conveyances, such as street cars, busses, suburban trains and the like. On the face of the card 4 is printed, in display type, a message designed to attract the attention of patrons of the conveyance and to enlist their interest in appropriating the pieces of literature 6.

The dimensions of such a display-card 4 would be de-

2

terminated by the message it was to contain and the arrangements in the conveyance for locating such display-cards. At one or more places on the card 4, depending upon circumstances, is a hole or aperture 7. The positioning 5 of such hole or aperture 7 well might depend upon the height of the display-card 4 in the conveyance and the nature and amount of the literature 6 to be displayed.

The literature-mounting element 5 here is shown in the form of a plate 8 an integral portion of which extends outwardly from one face 9 thereof to form an upwardly-opening hook 10. The element 5 may be metal, with a medial portion thereof struck out and bent to form the hook 10. Or, the element 5 may be molded plastic.

The shape and dimensions of the element 5, as well as 15 the substance from which it is structured, may be a matter of choice. The herein shown element 5 is a piece of sheet metal of elongated rectangular contour. A longitudinally-medial portion thereof, between the opposite ends, is struck out from the face 9 and bent into the 20 shape of the upwardly-opening hook 10. The hook 10 thus is located adjacent what, in the normal use, is the top end 11. Preferably the hook 10 is formed with the two legs 12 and 13. The leg 12 is shown substantially 25 straight and extends outwardly downward from the plate face 9 at an angle of about 30 degrees from a plate normal through the point of the leg juncture with the plate 8 (FIG. 3). The juncture of the legs 11 and 12 is rounded and the leg 13 extends upwardly nearly parallel with the plane of the plate 8. The outer extremity of the leg 12 30 is curved slightly away from the plate 8.

The element 5 is mounted on the display-card 4 by inserting the hook 10 through the card hole or aperture 7, thereby positioning the plate flat against the back of the display-card 4 where it is held firmly in place. It 35 would be practically impossible to remove or tear the hooked plate 8 away from the card 4 without removal of the literature 6 and removal of the card 4 from the position in the public conveyance, as will be explained presently.

When such an advertising display-card 4, with its literature 6 is used in public conveyances, the card 4, with the suspension element 5 in place, is flexed to seat the lateral edges of the card 4 in grooves 14 in the conventional supporting frame 15 on the conveyance. The desired 40 amount of literature 6 would be placed on the hook 10 ready for removal by interested patrons using the conveyance.

The literature 6 here is shown in the form of tear-cards. 45 Obviously, these would be of appropriate size for use with the display-card 4. Generally, these tear-cards would be approximately post-card size, especially if they were to be mailed. At one end each card is formed with a punch-hole 15 to fit over the hook 10 of the element 5. 50 Where desired, the cards could have a series of one or more transverse perforations 16 and 17. One such transverse perforation 16 could permit severing the main part of the card from a narrow, punched-end section 18. Another transverse perforation 17 could be intermediate the 55 ends of the card to permit severing the two portions, one to be mailed, the other to be retained by the person removing a card from the hook 10.

From the foregoing it will be seen that a simply-formed suspension element 5, of the kind herein illustrated, inserted through the hole or aperture 7 in the card 4 provides a firm support for the literature 6 from which one piece at a time can be removed with no intentional or unintentional likelihood of dislodging the remaining pieces of the literature, or even deliberate or unintentional removing the element 5 by the public, without destruction 60 of the card 4.

Although but one specific embodiment of this inven-

tion is herein shown and described, it will be understood that details of the construction shown may be altered or omitted without departing from the spirit of the invention as defined by the following claim.

I claim:

A literature-suspending advertising display comprising a supporting, flexible, paper-stock card rectangular in contour and dimensioned for presenting a printed message and adapted for mounting in a conventional public conveyance display rack, the card having an aperture therein inwardly adjacent from one edge thereof, and a thin, flat, metal plate of miniature dimension compared with that of the card, the plate having a medial portion thereof, in width less than one-third the width of the plate, struck-up from one face of the plate, said struck-up portion being bent back upon itself to provide a reentrant portion

spaced from its juncture with the plate, the free end of the struck-up portion extending beyond the plate to form an upwardly-open hook, the plate being supported on the card flat against the back thereof solely by the hook being inserted through the card aperture with the reentrant portion of the hook spaced outwardly of the face of the card in substantially parallel disposition to suspend literature therefrom accessible for removal by interested persons without any possible dislodgment of the plate from the card or rupture of the card.
